his

UNITED STATES PATENT OFFICE.

BENGT M. W. HANSON, OF HARTFORD, CONNECTICUT.

GAUGE

Application filed April 16, 1921. Serial No. 461,956.

To all whom it may concern:

Be it known that I, BENGT M. W. HANSON, a citizen of the United States, and resident of Hartford, county of Hartford, State of Connecticut, have invented certain new and useful Improvements in Gauges, of which the following is a specification.

This invention relates to gauges. In the present illustrative disclosure, the invention is shown as incorporated in a gauge for screw threaded members, to which use it is peculiarly applicable. It is to be understood that the present disclosure is by way of illustration only, as the invention is susceptible of other embodiments than those herein shown.

The aim of the invention is to provide a gauge having various features of novelty and advantage, and more particularly to provide a device of this sort with which threaded members may be very readily and accurately gauged within predetermined limits of tolerance.

In the accompanying drawing, Fig. 1 is a side elevation of a gauge illustrating one embodiment of the present invention, looking in the direction of the arrow 1 of Fig. 3.

Fig. 2 is a cross sectional view thereof looking in the direction of the arrow 2, Fig. 3.

Fig. 3 is the sectional view taken on line 3—3 of Fig. 1, looking in the direction of the arrow 3.

Fig. 4 is a view similar to Fig. 1 but illustrates another embodiment of the invention.

Referring to that embodiment of the invention shown in Figs. 1 to 3 inclusive, *a* is a frame in the form of a C having a pair of heads 9, 10 on the opposed faces of which are mounted jaws *b*, *c*, each of which, in the present instance, comprises a single member or block. The opposed jaw faces are provided, respectively, with teeth or serrations 11, 12, each similar in transverse section to the groove of the thread to be gauged, except that the serrations may not be as deep as the groove. The serrations on each jaw face are parallel to each other, but the serrations of one jaw face are oppositely inclined laterally to those of the other face, in accordance with the angle between diametrically opposite portions of the thread to be gauged, so that the threads and the serrations at their points of contact extend in the same direction. In Fig. 3, the line *s*—*s* de-

notes the central plane to which the serrations 11, 12, are oppositely inclined at like angles. The axis of the threaded member, when inserted between the jaws, will be at 60 right angles to this plane indicated by the transverse line *t*—*t*. It will be understood that the pitch of the serrations of each jaw face corresponds with the pitch of the thread to be gauged.

To accommodate the lead of the thread to be gauged, one of the jaw members, in the present instance the member *b*, is mounted for transverse movement in the direction of the line *t*—*t*. To this end, the block *b* is provided with a tongue 14 having a sliding fit in a groove 15 in the head 9 and this block is resiliently held to its seat by a spring 16 coiled about a screw 17 threaded into the block and extending through a slot 18 in 75 the head.

For the purpose of gauging threaded members within specified working allowances or tolerances, the arrangement is such that the jaws are slightly inclined toward 80 one another in a direction longitudinally of the serrations and indicating means are provided to denote the respective points past which a threaded member should and should not go to be within the specified limits of accuracy; also means are provided for adjusting the faces relative to one another to permit of variation in working allowances and to take up wear. To these ends, in the embodiment shown in Figs. 1 to 3, the jaw member *c* is adapted to be adjusted by a wedge 20 so that the jaw faces are longitudinally inclined relative to one another, that is, in the direction of the line *s*—*s*. The wedge 20 is positioned in an inclined groove 26 extending transversely of the head 10, and is adjusted by a screw 27. The jaw member *c* is secured to the head by a screw 28, there being sufficient play between the parts to permit of angular adjustment thereof. This member *c*, adjacent its rear end, is supported by an adjustable screw 29 which constitutes the fulcrum for the member *c* when the latter is adjusted by means of the wedge. The jaw face of the member *c* is 95 transversely grooved as at 21 and the forward edge 22 of this groove may be employed to indicate the point past which the threaded member must go to be below the maximum limit of accuracy, and the rear edges 23 of the serrations 11, 12, may be 100 employed to indicate the point past which

105

110

the threaded member should not go to be above the minimum limit of accuracy. On the side face of the member b is a scale 24 which is of assistance in determining the 5 exact diameter of the threaded member.

Assuming, for purposes of illustration, that the gauge is particularly constructed for measuring threaded members one inch in diameter, and the specified limits of accuracy for the particular threaded member 10 to be gauged are one inch and one inch minus .002, the procedure is as follows:— The jaw c is adjusted relative to the other jaw b by means of the wedge 20 and the screw 29 until a threaded test piece having a diameter of exactly .998" will just fail to pass between the rear edges 23 of the jaw faces, and a second test piece of exactly one inch diameter will just slide past 15 the forward edge 22 of the groove 21. The taper of the jaws relative to one another between the edges 22, 23, and which may be respectively referred to as the "go" and "not go" points, will now be equal to the 20 working allowance, namely .002". The threaded member to be gauged is now inserted between the jaws, and the lead of the thread will cause the member b to move transversely, it being guided in this movement by the tongue and groove arrangement 25 14, 15. If the threaded member can be moved past the "go" point 22, but not past the "not go" point 23, it is necessarily within the limits of tolerance. The exact size of the threaded member can be determined by noting on the scale 24 that point at which the threaded member closely fits between the jaws. By holding the gauge between a source of light and the eye and sighting 30 40 along the serrations, it can be readily determined whether each of the convolutions of the thread is accurate as to shape and size. Since each of the jaw faces has a relatively large number of serrations, permitting of measurement of the threaded member for a considerable distance, any errors in the pitch of the threaded member will become immediately apparent. It is evident that by adjusting the wedge 20 and the 45 screw 29 wear between the jaw faces may be readily taken up, and the inclination of these faces relative to one another may be varied in accordance with changes in working allowances. It will further be seen 50 55 that the handle or connecting portion of the frame is at an angle, say 45° , to the length of the serrations so that this handle does not obstruct the light in the line of the serrations, nor interfere with the insertion of a relatively long threaded member between the jaws.

In the embodiment shown in Fig. 4, the jaw b' is similar to the jaw b of the previous embodiment, and is mounted for 60 65 transverse movement. The opposing jaw

on the head 10 comprises a pair of elongated blocks or sections c' , c'' , spaced one back of the other and extending transversely of the jaw b' . The active face of each of these sections is in the form of a 70 segment of a screw, similar in all respects to the member to be gauged but running in the opposite direction; that is to say, if the gauge is constructed to gauge right handed screw threads, the sections c' have 75 serrations or teeth comprising segments of a left hand screw, and vice versa. Associated with each section c' is a wedge 20' adapted to be adjusted by a screw 27' so that the sections c' may be adjusted relative 80 to the jaw b' to establish the specified limits of tolerance, and to take up wear. The sections c' are secured to the head 10 by bolts 30, it being understood that the wedges 20' are provided with slots through which 85 these bolts extend.

It will be understood that with the gauge constructed in accordance with the embodiment of Fig. 4, the front section c' will be adjusted so that the distance between the 90 high point of the active face of this section and the jaw face of the member b' will be equal to the specified maximum limit of accuracy of the thread to be gauged and the distance between the high point of the 95 rear section c' and the face of the jaw member b' will equal the specified minimum limit of accuracy. In one manner of speaking, the active faces of the sections c' collectively constituted a jaw opposed to the 100 other jaw b' . By adjusting these sections the plane of the active gauging surfaces thereof, as indicated by the line $p-p$, may be adjusted angularly relative to the opposing jaw b' .

It is obvious that the invention is susceptible of various modifications and changes which are within the spirit of the invention without departing from the scope of the following claims; for instance, the jaw 110 member b' in the embodiment of Fig. 4 instead of being in the form of a single block may be constituted of a pair of sections similar to sections c' . It is to be understood that the present disclosure of the invention 115 is by way of illustration only and is not to be taken as restrictive of my conception. The detailed construction of the embodiment shown in Fig. 4 is reserved for a separate application.

I claim as my invention:—

1. A gauge provided with a pair of opposed jaw faces, each having a plurality of serrations corresponding in cross section to the groove of a threaded member and spaced apart in accordance with the pitch thereof, the serrations of one face being laterally inclined to those of the other face, said jaw faces being inclined towards each other longitudinally of said serrations. 120 125 130

2. A gauge provided with a pair of opposed jaw faces inclined towards each other and each having a plurality of serrations extending in the general direction of inclination of said faces with the serrations of one face laterally inclined to the serrations of the other face and transverse edges on said faces denoting the points past which a threaded member should go to be within predetermined limits of accuracy. 5
3. A gauge provided with a pair of opposed jaw faces inclined towards each other, each having a plurality of serrations extending in the general direction of inclination of said faces, one of said faces being transversely grooved between its ends to provide a gauging edge. 10
4. A gauge comprising a pair of cooperating gauging members each of which has a plurality of gauging points, one of said members being mounted for transverse movement during the gaging operation. 15
5. A gauge comprising a pair of cooperating gauging members each of which has a plurality of gauging points, one of said members being mounted for transverse movement during the gaging operation, and one of said members being mounted for angular movement. 20
6. A gauge provided with a pair of opposed jaw faces each having a plurality of serrations, the serrations of one face being inclined to those of the other in accordance with the angle between diametrically opposite portions of a thread to be gauged, one of said jaws being mounted for transverse movement. 25
7. A gauge provided with a frame, a pair of jaw members mounted thereon with their opposed faces provided with a plurality of serrations, the serrations of one jaw face being inclined to those of the other face in accordance with the angle between diametrically opposite portions of a thread to be gauged, said jaw faces being inclined towards each other in the direction of the length of said serrations, one of said jaw members being supported on said frame for transverse sliding movement. 30
8. A gauge provided with a pair of opposed jaw faces, and means for angularly adjusting one of said faces relative to the other, one of said faces being transversely grooved to provide a gauging edge. 35
9. A gauge provided with a pair of opposed jaw faces, each having a plurality of serrations, the serrations of one face being laterally inclined to those of the other, and means for angularly adjusting said faces relative to one another. 40
10. A gauge provided with a pair of opposed jaw faces, each having a plurality of serrations, the serrations of one face being laterally inclined to those of the other face, means for angularly adjusting said faces 45
- relative to one another in the general direction of the length of said serrations, and spaced gauging points spaced along said serrations. 50
11. A gauge provided with a pair of opposed jaw faces, each provided with a plurality of serrations, the serrations of one face being laterally inclined to those of the other in accordance with the angle between diametrically opposite portions of a threaded member to be gauged, means for angularly adjusting said faces one relative to the other, means for guiding one of said members transversely, and transverse edges on one of said faces and spaced apart longitudinally thereof for denoting the points past which a member should and should not go to be within predetermined limits of accuracy. 55
12. A gauge provided with a frame, jaw members thereon having opposed jaw surfaces provided with a plurality of serrations and a wedge interposed between said frame and one of said members and movable transversely of the serrations thereof for angularly adjusting said member relative to the other one. 60
13. A gauge provided with a frame, opposed jaws thereon, an adjustable fulcrum on said frame for one of said jaws, and a wedge between said frame and said last mentioned jaw for adjusting the latter. 65
14. A gauge provided with a frame, opposed jaws, means for securing one of said jaws to said frame for angular adjustment, an adjustable screw carried by said frame and supporting one end of said last mentioned jaw, and an adjustable wedge interposed between said frame and the other end of said jaw. 70
15. A gauge comprising a frame having a connecting portion and oppositely positioned heads carried thereby, gauging members on opposing faces of said heads, said gauging members having thread gauging faces disposed with their lengths extending transversely of the plane of said connecting portion. 75
16. In a gauge, a C-frame, and a pair of jaw members carried thereby and each provided with serrations extending transversely of the plane of the connecting portion of said frame. 80
17. A gauge provided with a frame, jaw members thereon having opposed jaw faces having a plurality of serrations, means for securing one of said jaw members to said frame for angular movement, an adjustable screw carried by said frame and supporting one end of said last mentioned jaw member, and an adjustable wedge interposed between said frame and the other end of said member and movable transversely of the serrations of the latter. 85
